Primary Examiner — Wendy L Arminio(74) *Attorney, Agent, or Firm* — P. Scott Smith(57) **CLAIM**

The ornamental design for a cap dispenser, as shown and described.

DESCRIPTION

FIG. 1 is a top perspective view of a cap dispenser embodying the new design;

FIG. 2 is a bottom perspective view thereof;

FIG. 3 is a front side elevation view thereof;

FIG. 4 is a rear side elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines are included for the purpose of illustrating the portions of the cap dispenser that form no part of the claimed design.

1 Claim, 8 Drawing Sheets(56)
